UNITED STATES PATENT OFFICE.

THOMAS F. PAYNE, OF PITTSBURG, PENNSYLVANIA.

FLUSHING-VALVE.

No. 901,467.

Specification of Letters Patent.

Patented Oct. 20, 1908.

Application filed October 3, 1907. Serial No. 395,677.

To all whom it may concern:

Be it known that I, THOMAS F. PAYNE, of Pittsburgh, in the county of Allegheny and State of Pennsylvania, have invented a certain new and useful Improvement in Flushing-Valves, of which the following is a full, clear, and exact description, reference being had to the accompanying drawings, forming part of this specification, in which—

Figure 1 is a rear elevation of a valve illustrating my invention; Fig. 2 is a side elevation, partly in section; Fig. 3 is a vertical section showing the valve in its lowered position; Fig. 4 is a vertical section showing the valve in its raised position; Fig. 5 is a rear elevation partly in section; Fig. 6 is a vertical section on the line 6—6 of Fig. 3; Fig. 7 is a front elevation of a modification; Fig. 8 is a side elevation of the same; Fig. 9 is a front elevation of a second modification; Fig. 10 is a plan view of the same partly in section; Fig. 11 is a section on the line 11—11 of Fig. 9 showing the valve open; Fig. 12 is a like view showing the valve closed; Fig. 13 is a section on the line 13—13 of Fig. 9; and Fig. 14 is a section on the line 14—14 of Fig. 12.

Heretofore in flushing valves for water-closets of that class in which the bowl is flushed by the direct flow of water from the main, and is controlled by the filling of the valve chamber, the aperture which permits the flow of water to the upper face of the valve, to create a closing pressure, is minute and apt to be clogged by foreign matter which may be suspended in the water, whereby the operation of the valve is often interrupted, requiring the valve to be taken apart and cleaned. Another difficulty has been found in closing the valve where pressure in the water main is insufficient or becomes low, which allows the water to pass through the valve without power to close the same. Another difficulty has been found in the necessity of taking the valve apart in order to adjust it to the amount of water to be delivered to the bowl, or the length of time it is desired the valve shall remain open.

The object of my invention is to obviate these objectionable features, and it consists in a valve having devices for causing a reverse flow of water through the filling aperture whereby the same is continually washed out and kept clean, in devices for creating a partial vacuum in rear of the operating piston, and in devices for adjusting the valve,

and it also consists in devices and features of construction hereinafter more fully set forth.

I will now describe my invention so that others skilled in the art may employ the same.

In the drawing, 2 represents the threaded socket or inlet adapted to communicate with the water main, and 3 and 3^a represent the valve chamber, the upper portion 3 of which is of greater area in cross section than the lower portion 3^a. At the lower portion of the valve chamber 3^a is the valve-seat 4. Situate in the valve chamber is a piston valve 70 having an upper piston head 5 located in the upper portion 3 of the valve chamber and a lower piston head 6 and a valve 7 located in the lower portion 3^a of the valve chamber. The piston heads 5 and 6 are provided with washers or packing 5^a and 6^a which fit tightly against the walls of that portion of the valve chamber in which they are respectively located. The valve 7 is provided with a washer 7^a adapted to close the water-way 80 of the valve-seat 4. The piston-heads 5 and 6 and the valve 7 are mounted on the stem 8. The valve chamber 3^a communicates by the passages 9 with the pipe 10 that leads to the bowl. This pipe 10 is shut off by the partition 11 from direct communication with the inlet 2. Leading from the inlet 2 is an inlet by-pass 12, which at its other end communicates with the port 13 of the plug 14 of the cock 15, the passage of communication between the passage 12 and the port 13 being minute, although the passage 12 and the port 13 are of much larger area. In the bushing 16 of the plug 14 is a port 17 which communicates with the outlet by-pass 18 that leads to the passage 9. The plug 14 is provided with a central cavity 19 that communicates with the port 13 and opens into a passage 20 which leads to and opens into the upper portion of the valve-chamber 3 above the piston head 5. The plug 14 is provided with a lever arm 21 having a slot in which is located a pin 23 extending from the push button 24 which is supported by the spring 25 in the casing 26. At the top of the casing 26 is a screw cap 27, the bottom of which acts as a stop to the movement of the arm 21, so that by adjusting the screw cap the size of the opening between the passage 12 and 13 may be regulated, thus regulating the time of closing of the valve 7. Below the valve washer 7^a is a plug 27, of slightly less diam-

eter than the valve casing, which plug serves to choke the flow of water before the valve closes and yet permits the bowl to refill at the close of the flushing action.

5 In Figs. 7 and 8 I show a modification in which the push button 24^a is arranged horizontally, connected with the lever 21^a, and is adapted to extend through a wall.

10 In Figs. 9, 10, 11, 12, 13, and 14 I show a modification in which the plug 14^b and the push button 24^b are placed on top of the valve casing instead of at the side thereof. In this modification the connection with the water main pipe is at 2^b and the pipe leading 15 to the bowl is at 10^b. The piston valve having the heads 5^b and 6^b and the valve 7^b are of different shape and the location of the parts is different from that shown in the other figures. In this modification the cavity 19^b and port communicate directly with the valve chamber 3^b.

20 In my improved valve or "metric flush" the parts are normally in the position shown in Figs. 1, 2, and 3, there being a minute opening between the passages 12 and 13 which allows water to flow from the inlet 2 through the passage 20 to the upper portion 3 of the valve chamber where it exerts downward pressure against the piston head 5, 25 which is of greater area than the lower face of the valve 7 against which the water from the inlet 2 exerts an upward pressure. This downward pressure therefore normally keeps the valve 7 closed against its seat 4 and prevents water from flowing to the bowl. When 30 the push button 24 is pressed downwardly against the force of the spring 26, the lever 21 gives a partial rotation to the plug 14 which carries the port 13 from the inlet passage 12 to and into communication with the outlet port 17 and passage 18. This shuts off the water communication between the inlet 2 and the chamber 3 and opens a free passage 35 between the chamber 3 and the passage 18 against which is merely atmospheric pressure. The pressure of the water below the valve 7 thereupon becomes greater than the pressure on the piston head 5 and the valve 7 is forced upward in the chamber 3^a, causing 40 the water in the chamber 3 to be forced out through the passages 20, 19, 17 and 18, and permits the water from the inlet 2 to flow in volume through the passages 9 and pipe 10 to the bowl, thus flushing the closet. The 45 packing of the piston head 6 fitting closely in the chamber 3^a serves to keep the pressure of the water in the main from being exerted against the lower side of the piston head 5.

50 When it is desired to stop the flow of water through the pipe 10, the push button 24 is released and the spring 25 carries it and the lever 21 back to their normal positions and turns the plug 14, bringing the port 13 out of communication with the passage 18 and again in such partial register

55 with the passage 12 as to form a minute opening between the passage 12 and the port 13, which again permits the water from the inlet 2 to flow through the passages 12, 13, 19, and 20 into the chamber 3, and there 60 to gradually close the valve 7 under the greater pressure above the piston head 5 than exists below the piston head 6. During 65 this slow closing movement the water continues to flow in volume to the pipe 10 until the plug 27 enters the contracted portion of the valve casing below the valve seat and chokes the flow of water, permitting only sufficient water to pass the valve as is necessary to refill the bowl. As the 70 cross area of the chamber 3 is greater than the cross area of the chamber 3^a, the upward movement of the piston heads 5 and 6 creates a partial vacuum behind the piston head 5 which aids in the return movement of the 75 same.

80 The advantages of my invention result from the construction which causes the outflow of water from the valve chamber to pass through the inlet port in a reverse direction keeping this passage at all times clean and free from obstructions that would interfere with the operation of the valve; also from the devices which enable a small 85 pressure of water to close the valve; and from devices outside of the valve and by means of which the time occupied in the closing of the valve may be regulated.

85 Many modifications in addition to those shown in the drawings may be made in the 90 form and location of the parts without departing from my invention.

95 Although I have shown my invention applied to a valve for flushing water-closets, I do not desire to limit it to this use.

100 Having thus described my invention, what I claim and desire to secure by Letters Patent is

1. In a flushing valve, the combination of 110 a valve chamber having an imperforate side wall, a piston valve having heads of different areas spaced apart, a passage leading to the valve chamber in rear of valve head of greater area, an inlet, an outlet, a plug having a cavity registering in all positions 115 with the passage leading to the valve chamber, and said cavity having a port arranged in one position to partially uncover the inlet and in another position to completely open the outlet.

120 2. In a flushing valve, the combination of 125 a valve chamber, a piston valve operating therein, a passage leading to the valve chamber, an inlet, an outlet, and a plug having a cavity registering in all positions with said passage, and said cavity having a port arranged in one position to partially uncover the inlet and in another position to completely open the outlet.

3. In a flushing valve, the combination of 130

a valve chamber, a piston valve operating therein, a passage leading to the valve chamber, an inlet, an outlet, and a plug having a cavity registering in all positions with said passage, and said cavity having a port registering in one position with the inlet and in another position with the outlet, and an operating mechanism for manually controlling the opening of said plug, having, 10 automatic means for closing said plug and means for adjusting the amount of said closing movement.

4. In a flushing valve, the combination of a valve chamber, a piston valve operating therein, a passage leading to the valve chamber,

ber, an inlet, an outlet, and a plug having a cavity registering in all positions with said passage, and said cavity having a port registering in one position with the inlet and in another position with the outlet, and 20 an operating mechanism connected with said plug having means for adjusting the amount of movement of the plug.

In testimony whereof, I have hereunto set my hand.

THOMAS F. PAYNE.
